US0D1067822S

(12) **United States Design Patent** (10) Patent No.: **US D1,067,822 S**
Phillips et al. (45) Date of Patent: ** Mar. 25, 2025

(54) **VEHICLE, TOY REPLICA, AND/OR OTHER REPLICA**

(71) Applicant: **GM GLOBAL TECHNOLOGY OPERATIONS LLC**, Detroit, MI (US)

(72) Inventors: **Logan J. Phillips**, Farmington Hills, MI (US); **Namwoo Kim**, Sterling Heights, MI (US); **Conner J. Stormer**, Detroit, MI (US); **Dave W. Heyne**, Hazel Park, MI (US)

(73) Assignee: **GM GLOBAL TECHNOLOGY OPERATIONS LLC**, Detroit, MI (US)

(**) Term: **15 Years**

(21) Appl. No.: **29/892,872**

(22) Filed: **May 23, 2023**

(51) LOC (15) Cl. **12-08**

(52) U.S. Cl.

USPC **D12/87**
